UNITED STATES PATENT OFFICE

2,367,309

PAINTING MACHINE

Frank Allen Parker and Frederick Ancliff,
Drummondville, Quebec, Canada, assignors to
Celanese Corporation of America, a corporation
of Delaware

Application October 7, 1942, Serial No. 461,090

11 Claims. (Cl. 91—46)

This invention relates to a painting machine, and relates more particularly to a machine for painting the tips of pirn tubes or similar yarn holders.

Yarn packages are normally supplied with means for identifying the characteristics, i. e., twist, denier, count, etc., of the yarn wound thereon. In pirn tubes the identification mark usually takes the form of a painted tip, different colors of paint indicating different yarn characteristics. Heretofore, these tips were painted by hand with a brush or by dipping the same in a vessel containing the coloring medium. The manual pirn tube tip painting was a slow and laborous process. It is, accordingly, an important object of this invention to provide an improved means for coloring the tips of pirn tubes automatically and expeditiously.

Another object of this invention is to provide a machine for automatically coloring the tips of pirn tubes which obviates the use of a brush for applying coloring matter to said tubes.

Still another object of this invention is to provide, in a machine for coloring the tips of pirn tubes, means for positively drying the colored pirn tip before it leaves the machine.

Other objects of this invention, together with certain details of construction and combinations of parts, will appear from the following detailed description.

In the accompanying drawings wherein the preferred embodiment of this invention is shown:

Figure 1 is a side elevational view of the machine of this invention,

Figure 2 is a top plan view of the same,

Figure 3 is a cross-sectional view, taken on line 3—3 in Figure 2, on an enlarged scale, and

Figure 4 is a vertical sectional view through the machine.

Like reference numerals indicate like parts throughout the several views of the drawings.

In one aspect, this invention comprises a framework on which is suitably mounted a carrier having an orbital movement for conveying the pirns past a number of stations whereat the tips of the pirns are painted, the excess paint removed and the painted tips dried.

Referring now to the drawings, the reference numeral 5 generally indicates a channel-iron framework which is carried on a support 6. Fixed at one end of framework 5 is a bearing bracket 7 having bearings 8 in which is journaled a vertical shaft 9 on the upper extremity of which is mounted a pulley 11. This pulley is driven by means of a motor 12 connected by belt 13 and pulleys 14 and 15 to worm shaft 16 of a duplex worm

gear reducer generally indicated by reference numeral 17. The slow speed shaft 18 of the worm gear reducer 17 is vertical and is directly connected by means of a flexible slip coupling, generally indicated by reference numeral 19, to the shaft 9 of the driven pulley 11. The slip coupling 19 is provided as a safety link in case of jamming or trapping of the operator's hand in the apparatus. The motor and reducer are carried on a platform 20 supported by legs 6.

At the end of the framework opposite to end carrying shaft 9 is mounted a table 21 having thereon bearing bracket 22 integral with which are bearings 23. In these bearings 23 is journaled vertical shaft 24 of idler pulley 25. An endless belt 26 is mounted on pulleys 11 and 25 which may be flanged to maintain the belt thereon. The table 21 may be moved along framework 5 by means of a screw bolt 26' carried on a cross-piece 27 and attached to the table, the table being secured in any desired position by locknuts 28 on the screw bolt 26 as well as bolts 29 passing through slots 31 to fasten the table 21 to framework 5. The mounting of the idler pulley 25 on adjustable table 21 permits of the ready tightening of belt 26.

The belt 26 carries a series of clips 32 adapted to hold loosely pirn tubes 33 in such a manner that the shoulder 34 of the ferrule 35 rests on the top of the clip. The pirn tubes 33 are loaded manually in the clips 32 as they come around the drive pulley 11 and, as the belt 26 rotates in a clock-wise direction, the tips of the pirn tubes carried in the clips engage a ramp 36. This ramp causes the pirn tubes to be raised about one-eighth of an inch when they have reached the top thereof, thus raising the shoulder of the ferrule the same distance above the top of the clip. As the pirn tube is caused to travel along, the ferrule enters between two bent metal strips 37 forming a ramp which the shoulder 34 of the ferrule engages and slides upward the distance necessary to clear the edge 37' of a trough 38 containing the paint to be applied to the pirn tube tips. The ramp 37 is of such length and of such construction as to permit the pirn tubes to fall off the same on to the clips after the edge of the paint trough 38 has been cleared. Supported by the clips 32, the pirn tube tips are immersed to the desired depth in the paint in the trough 38. The extent of immersion of the tip in the paint trough may be adjusted if desired.

While the pirn tube travels along in paint trough 38, it is preferably rotated. To this end there is provided a rubber covered rod 39 resiliently held against the travelling pirn tubes by a bent wire

41 suitably fixed to a support 42 attached to framework 5. The light pressure of rod 39 against the purn tubes as they are carried past said rod causes the purn tubes to rotate insuring uniform application of paint to the tips thereof. After travelling a short distance, say, about two inches, through the paint, the purn tubes are again raised by a ramp 43 similar in construction and operation to the ramp formed by metal strips 37. Ramp 43 causes the purn tubes to clear the other edge 44 of paint trough 38, the purn tubes then dropping on clips.

The belt 26 then carries the purn tubes under an air jet 45 (shown closed in Figure 1 and open in Figure 3) which blows air through the opening in the purn tube thus blowing out any paint collected in the tip opening. This paint is collected in a suitable vessel 46 and reclaimed.

The purn tubes then pass around idler pulley 25 to the opposite side of the machine where means are provided for drying the painted tips of the purn tubes. This means comprises a fairly long U-shaped trough 47 of a suitable metal, preferably lined with asbestos sheeting 48, carried by a series of bolts 49 adjustably mounted on a bracket 51 fixed to framework 5. The drying trough is provided with heating means 52 in the form of electric strip heaters placed along the bottom thereof. After the purn tubes emerge from the drying trough 47, they are automatically discharged from the clips by means of one or more stationary fingers 53 and may fall and be collected in any suitable container.

Means are provided at various parts of the machine to prevent the purn tubes from falling out of the clips. Such means are bent wire guards 54 positioned one on each side of ramp 36 and rods 55, 56 and 57. Rods 55 and 57 are supported from framework 5 by means of bent rods 58 and rod 56 is supported by bent rods 59 attached to cross-pieces 61 and 62 on a bracket 63 fixed to framework 5.

Paint or coloring matter is supplied to paint trough 38 from a glass bottle 64 carried in a cradle 65 mounted on a suitable support 66. This support, together with the cradle and bottle, may be vertically adjustable by raising or lowering the screw-bolts 67 by which the support is fixed to and carried above the framework 5, the screw-bolts being maintained in adjusted position by means of locknuts 68. The bottle 64 is provided with glass tubes 69 and 71 extending into trough 36 for supplying paint thereto and maintaining the desired level of paint therein.

While this machine has been described in connection with the painting of purn tube tips, it is also applicable to the painting of the tips of any yarn holders having a shoulder thereon which could be supported in the clips.

It is to be understood that the foregoing detailed description is given merely by way of illustration and that many variations may be made therein without departing from the spirit of our invention.

Having described our invention, what we desire to secure by Letters Patent is:

1. In a machine for coloring the tips of yarn holders, the combination with means for applying coloring matter to the tips of yarn holders, of a movable endless belt for conveying the yarn holders to said coloring matter applying means, means on said endless belt for receiving the yarn holders, and means for raising the yarn holders in said receiving means and for permitting the

lowering of the yarn holders in said receiving means by gravity.

2. In a machine for coloring the tips of yarn holders having a flange thereon, the combination with means for applying coloring matter to the tips of yarn holders, of a movable endless belt for conveying the yarn holders to said coloring matter applying means, means on said endless belt for receiving the yarn holders, and means for cooperating with the flanges of said yarn holders for raising the yarn holders in said receiving means and for permitting the lowering of the yarn holders in said receiving means by gravity.

3. In a machine for coloring the tips of yarn holders having a flange thereon, the combination with means for applying coloring matter to the tips of yarn holders, of a movable endless belt for conveying the yarn holders to said coloring matter applying means, means on said endless belt for receiving the yarn holders, and stationary means for cooperating with the flanges of said yarn holders for raising the yarn holders in said receiving means and for permitting the lowering of the yarn holders in said receiving means by gravity.

4. In a machine for coloring the tips of yarn holders having a flange thereon, the combination with means for applying coloring matter to the tips of yarn holders, of a movable endless belt for conveying the yarn holders to said coloring matter applying means, means on said endless belt for receiving the yarn holders, and ramps for cooperating with the flanges of said yarn holders for raising the yarn holders in said receiving means and for permitting the lowering of the yarn holders in said receiving means by gravity.

5. In a machine for coloring the tips of yarn holders having a flange thereon, the combination with a container for holding coloring matter to be applied to the tips of the yarn holders, of a movable endless belt for conveying the yarn holders to said container, means on said endless belt for receiving the yarn holders, and means for cooperating with the flanges on said yarn holders for moving the yarn holders in said receiving means so as to raise the yarn holders above the edge of the container and permit the lowering of the yarn holders in said container by gravity.

6. In a machine for coloring the tips of yarn holders having a flange thereon, the combination with a container for holding coloring matter to be applied to the tips of the yarn holders, of a movable endless belt for conveying the yarn holders to said container, means on said endless belt for receiving the yarn holders and stationary means for cooperating with the flanges on said yarn holders for moving the yarn holders in said receiving means so as to raise the yarn holders above the edge of the container and permit the lowering of the yarn holders in said container by gravity.

7. In a machine for coloring the tips of yarn holders having a flange thereon, the combination with a container for holding coloring matter to be applied to the tips of the yarn holders, of a movable endless belt for conveying the yarn holders to said container, means on said endless belt for receiving the yarn holders, and ramps for cooperating with the flanges on said yarn holders for moving the yarn holders in said receiving means so as to raise the yarn holders above the edge of the container and permit the lowering of the yarn holders in said container by gravity.

8. In a machine for coloring the tips of yarn holders having a flange thereon, the combina-

tion with a container for holding coloring matter to be applied to the tips of the yarn holders, of a movable endless belt for conveying the yarn holders to said container, means on said endless belt for receiving the yarn holders, means for cooperating with the flanges on said yarn holders for moving the yarn holders in said receiving means so as to raise the yarn holders above the edge of the container and permit the lowering of the yarn holders in said container by gravity, and means for drying the colored tips of the yarn holders.

9. In a machine for coloring the tips of yarn holders having a flange thereon, the combination with a container for holding coloring matter to be applied to the tips of the yarn holders, of a movable endless belt for conveying the yarn holders to said container, means on said endless belt for receiving the yarn holders, ramps cooperating with the flanges on said yarn holders for moving the yarn holders in said receiving means so as to raise the yarn holders above the edge of the container and permit the lowering of the yarn holders in said container by gravity, and means for drying the colored tips of the yarn holders.

10. In a machine for coloring the tips of yarn holders having a flange thereon, the combination with a container for holding coloring matter to be applied to the tips of the yarn holders, of a movable endless belt for conveying the yarn holders to said container, clips on said endless belt for receiving the yarn holders, ramps cooperating with the flanges on said yarn holders for moving the yarn holders in said receiving means so as to raise the yarn holders above the edge of the container and permit the lowering of the yarn holders in said container by gravity, and means for drying the colored tips of the yarn holders.

5 the yarn holders in said clips so as to raise the yarn holders above the edge of the container and permit the lowering of the yarn holders in said container by gravity, means for causing the rotation of the yarn holders during their passage through the container, means for removing excess coloring matter from the yarn holders, and means for drying the colored tips of the yarn holders.

10 11. In a machine for coloring the tips of yarn holders having a flange thereon, the combination with a container for holding coloring matter to be applied to the tips of the yarn holders and means for supplying coloring matter to said container, of a movable endless belt for conveying the yarn holders to said container, clips on said endless belt for receiving the yarn holders, means 15 for retaining the yarn holders in said clips, ramps cooperating with the flanges on said yarn holders for moving the yarn holders in said clips so as 20 to raise the yarn holders above the edge of the container and permit the lowering of the yarn holders in said container by gravity, means for causing the rotation of the yarn holders during their passage through the container, means for removing the excess coloring matter from the 25 yarn holders, means for drying the colored tips of the yarn holders, said drying means comprising an electrically heated trough through which 30 said yarn holders are adapted to pass, and means for automatically discharging said yarn holders from said endless belt.
